United States Patent Office.

J. C. W. MAAS AND CARL FISCHER, OF HAMBURG, GERMANY.

Letters Patent No. 75,638, dated March 17, 1868.

IMPROVEMENT IN MACHINE FOR STAMPING LETTERS.

The Schedule referred to in these Letters Patent and making part of the same.

TO ALL WHOM IT MAY CONCERN:

Be it known that we, J. C. W. MAAS and CARL FISCHER, citizens of Hamburg, Germany, have invented a new and useful Machine for Stamping Letters and all other articles whatsoever, capable of receiving a stamped impression, and for cancelling stamps on letters and all other articles; and we do hereby declare that the following is a full, clear, and exact description of the construction and operation of the same, reference being had to the annexed drawings, making a part of this specification, in which—

Figure 1 is a vertical section of the entire machine, and

Figure 2 a horizontal section of the rollers A and B.

The machine consists of the following-named parts, acting as hereinafter described:

The chief parts are the rollers A and B. In the roller A are sunk the spring-points b, each of which consists of a spur surrounded by a spiral spring, the outer end of the spur being provided with a point. Around the axle of this roller is the fixed eccentric c, over which, when A turns, the under end of the spring-point b slips, and its spring is thereby pushed beyond the periphery of the roller. As soon as the spur of b has laid hold of and borne away one of the letters, Z, resting upon it, the rear end of the part b loses its point of support on the eccentric, c, and, by the action of the spiral spring on b, the needle is withdrawn from the surface of the roller. On the axle of this roller A is another eccentric, which moves with the axle and sets in motion the lever k, which has its turning-point in t. It is the office of this lever to push on slowly, from left to right, the box F, by the motion of the stork's bill on the ratchet n¹. The roller B has not a full surface, but its periphery is formed only by the three points of the stamp e, and by the two thin rubber conducting-wheels j, which seize and press against the full surface of the roller A, the letters moving between the two rollers A and B as soon as the needles let the letters go, while the stamps e make a legible impression on the letters. f is the bearing of the axle of the roller B. It affords full support only on the left side, whilst it has free play on the right, in order to let B make a backward movement, when a thicker letter than usual passes between the two rollers A and B. The spring g, which is strong enough not only to push B back to its point of support, but also to give the stamp e a strong impression, regulates the movement of B. M is a stationary vertically-inclined board, situated above the roller A, as shown in fig. 1, and employed, in conjunction with a horizontally-inclined board, M¹, in order to form a hopper or receptacle, M², for the letters to be stamped. The letters are piled upon the board M¹, and their edges rest against the surface z of the board M, which serves as a guide to conduct the letters to the throat or opening between the lower end of said board M and the periphery of the roller A. Attached to the lower end of the board M is a series of thin springs, n, whose free ends bear upon the periphery of the roller A, and permit the passage beneath them of but one letter at a time, the letter next above being held back by said springs until caught by the next feeding-needle after the lapse of the proper interval from the taking of the first. The springs n are reinforced and properly held up to their working position by the springs n¹. Over the surface of the board z run bands, which pass over the grooved roller u, and at w, over small rollers, so that they continue to move downward, in order to keep in constant movement toward the hopper the letters resting against the board M. u is set in motion by a cord, v, from the end of the axle of the fly-wheel C.

The inking-apparatus preferred in connection with this machine consists of two steel and two rubber rollers. The upper steel roller, h¹, forms, with the knife m, which is close against the roller, the ink-reservoir. On the axle of this roller is a double eccentric, which so moves the lever y that the latter raises the following rubber roller, h², in order to take the ink from h¹, and, as soon as the pressure of the lever relaxes, to carry it to and transfer it upon the distributing steel roller h³. Against the last constantly rotates the outermost and lowest rubber inking-roller h⁴, which gives off the ink to the stamps e of the roller B coming in contact with it. The motion of the inking-rollers proceeds from a small wheel, q, connected with the cog-wheel o. On the opposite end (not visible in the drawing, fig. 1) of the axle of h⁴, and on the opposite end of the inking-apparatus, is an endless screw, which extends to the axle of the roller h¹, and moves said roller in the usual manner. F is a box into which the letters fall after they have been stamped. It moves on the railway D, and is put in motion as described, by the lever k.

What we claim, is—

1. The roller A and holders b, with their springs and cams c, substantially as described.
2. The cylinders A and B, stamps e, and yielding pressure-device f g, all substantially as described.

J. C. W. MAAS,
CARL FISCHER.
